UNITED STATES PATENT OFFICE

ADOLF FRIZ, OF STUTTGART-CANNSTATT, GERMANY

PRESS

Application filed February 19, 1930, Serial No. 429,606, and in Germany March 1, 1929.

My invention relates to presses and more particularly to power presses.

It is an object of my invention to provide a press in which the advantages of mechanical and fluid operation are combined.

To this end I provide mechanical means for performing the primary stage of the pressing operation, and fluid-controlled means for performing its final stage.

10 My invention will be described in connection with a machine for pressing ply-wood, but it is to be understood that I am not limited to this particular type of machine but may adapt my invention to any type of 15 press, for instance to bailing presses.

Hydraulic presses are comparatively high, which is inconvenient as it is often necessary to provide a deep pit for accommodating the machine in a low shop. Such presses while 20 presenting the advantage that the operating pressure can be ascertained very exactly by pressure gauges throughout the operation, involve the drawback that their operation is slow, unless auxiliary cylinders are provided for performing the primary stroke 25 at a faster rate. On the other hand mechanical presses and more particularly presses equipped with electric motors operate at a higher rate but involve the drawback that 30 the operating pressure can be ascertained only from the power input of the motor, a system which is rather inaccurate.

These drawbacks are removed, according 35 to my invention, by a combined operating system. The primary stage is performed by mechanical means, for instance by a motor in combination with reduction gearing, racks or spindles, and the final stage is performed under the action of fluid under pressure, for 40 instance by a hydraulic machine.

In a preferred embodiment of my invention I provide a presser plate, a nut on the presser plate which is supported on a vertical spindle, or any number of nuts and 45 spindles as required, generally a pair of spindles, each with a nut. The spindle, or spindles, is held against rotation while a motor with a worm gear is provided for imparting rotation to the nut so as to raise and 50 lower the presser plate which is supported

on the nut or nuts. The spindle, or spindles, is adapted to be displaced axially and provided with a hydraulic piston.

The motor is operated during the primary stage of the pressing operation, i. e. until the 55 presser plate encounters a considerable resistance. The presser plate now becomes stationary and upon further rotation of the worm gear the spindle is raised. When the piston of the spindle has arrived at the upper 60 end of its stroke the current supply to the motor is switched off, preferably by automatic means and a pump is started for supplying liquid to the hydraulic cylinder. The 65 spindle with the presser plate now descends and performs the final stage under hydraulic pressure.

In the drawings affixed to this specification and forming part thereof a ply-wood press embodying my invention is illustrated diagrammatically by way of example.

In the drawings

Fig. 1 is an elevation,

Fig. 2 is an end elevation of the press, viewed from the right in Fig. 1, with the 75 motor removed, and

Fig. 3 is a section on the line III-III in Fig. 1, drawn to a larger scale.

Referring now to the drawings, the frame of the press is built up from vertical and horizontal sections. The pair of vertical sections constituting the upright at the left of the press is indicated at 1 and 2 in Fig. 2, 3 is one of the vertical sections constituting the upright at the right, 12 and 13 are channel sections connecting the upper, and 6 and 7 are channel sections connecting the lower ends of the uprights. 8, 9 and 10, 11 are channel sections extending across the vertical sections of the uprights above the channels 12, 13, and 5 is a bolster plate which is placed across the sections 6 and 7. 4 is the presser plate which is provided with a casing 18 for the reception of the reduction gearing as will be described.

14 and 15 are threaded spindles which are fitted between the sections of the two uprights. The lower end of each spindle is provided with a reduced extension 23 of square section which is inserted in a transverse bar 100

24 of each upright, as best seen in Fig. 2. The shoulder between the spindle and the extension absorbs the downward thrust on the spindle. The vertical extension prevents 5 rotation of the spindle but permits axial displacement in upward direction for a purpose which will presently be described. 16 and 17 are nuts or threaded sleeves which are mounted on the spindles 14 and 15, respectively, 19 is a worm gear on each nut, and 20, 20 are 10 worms which cooperate with the gears 19 on the respective nuts. 21 is a shaft which extends throughout the frame 18 of the presser plate 4 and on which the worms 20, 20 are keyed. 22 is an electric motor which imparts 15 rotation to the shaft 21.

25 are pistons at the ends of the spindles 14 and 15, as shown for the spindle 14 in Fig. 1, and 26 are hydraulic cylinders supported 20 by the transverse sections 8, 9 and 10, 11, in which cylinders the pistons 25 are fitted to slide. 28 is a pump, 27 is a liquid reservoir which is arranged above the cylinder 26 at the left end of the machine, 29 is the suction pipe, 25 30 is the delivery pipe of the pump 28, the suction pipe being connected with the reservoir, and 31 is a three-way valve at the end of the pipe 30. 34 is a pipe extending from the 30 three-way valve 31 to the reservoir 27, 35 is a pipe extending from the valve to the upper end of the adjacent cylinder 26, and 36 is a pipe extending from the valve to the upper end of the cylinder 26 at the opposite end of the press.

35 37 is a hot-water tank for supplying the heated parts (not shown) of the press.

38 33 is a switch in the circuit of the motor 22, and 38 is a dog on one of the spindles, for instance 15, as shown in Fig. 2, by which the 40 current is switched off when the spindle has arrived at the upper end of its stroke.

The operation of my press is as follows:—

When the material to be pressed, in the present instance ply-wood, has been placed 45 on the bolster plate 5 the valve 31 is set so as to connect the pipe 34 with the pipes 35 and 36, and to break the connection with the delivery pipe 30. Pressureless liquid from the tank 27 now penetrates into the cylinders so 50 that they are permanently filled with liquid. The pistons 25 are at the lower end of their stroke as shown at the left in Fig. 1.

The motor 22 is now started rotating the nuts 16 and 17 and lowering the presser plate 4 with the casing 18. The downward movement of the presser plate continues until the resistance of the partly compressed material between the plates 4 and 5 has become equal to the thrust exerted on the presser 55 plate 4 by the spindles 15. The spindles now begin to rise upon continued rotation of the nuts 16 and 17 until the pistons 25 have arrived at the upper end of their stroke. The liquid from the cylinders is returned to the 60 reservoir 27 through the pipes 35, 36, and 34.

The square extensions 23 are so long that they will not move out of their holes in the transverse bars 24 when the spindles are shifted so that the spindles are held against rotation in any position. When the pistons 25 have 70 arrived at the upper end of their stroke, the current of the motor 22 is cut out, preferably by the automatic means 33, 38. The valve 31 is placed so as to connect the pipe 30 with the pipes 35 and 36, and to break the connection of these pipes with the pipe 34, and the pump 28 is started. Liquid from the reservoir 27 is drawn into the pump 28 through the suction pipe 29 and delivered to the cylinders 26 through the delivery pipe 30 and the pipes 35, 36, forcing down the pistons in 75 these cylinders and applying the presser plate 4 to the material. When the desired pressure has been attained, the pump 28 is arrested. The pressure is read exactly at a pressure 80 gauge (not shown) as in any hydraulic machine. When it is desired to return the parts to their initial position the connection of the pipes 35 and 36 with the pipe 34 is reestablished so that the liquid from the cylinders 85 can be discharged into the reservoir 27 where it is not under pressure and the motor 22 is started.

The principal advantage of my novel press is that its operation is rapid as compared 95 with a normal hydraulic press while at the same time the operating pressure can be read throughout the final stage.

The overall height of the press is much reduced as compared with the normal hydraulic presses, and the press is a self-contained unit 100 which does not require a foundation and pits or the like.

All auxiliaries can be fitted to, or built into, the press in convenient position, so that a very 105 suitable self-contained unit is obtained.

Other means than spindles, for instance racks, may be provided for reciprocating the presser plate mechanically.

I wish it to be understood that I do not desire to be limited to the exact details of construction shown and described for obvious modifications will occur to a person skilled 110 in the art.

In the claims affixed to this specification no 115 selection of any particular modification of the invention is intended to the exclusion of other modifications thereof and the right to subsequently make claim to any modification not covered by these claims is expressly reserved.

I claim:—

1. A press comprising a frame, a bolster plate, a threaded spindle fitted to slide in said frame but held against rotation, a nut on said spindle, a presser plate supported on said nut, means on said presser plate for imparting rotation to said nut, a piston at the end of said spindle, a cylinder in which said pis- 120 125 130

ton is fitted to slide, and means for supplying fluid under pressure to said cylinder.

2. A press comprising a frame, a bolster plate, a threaded spindle, a thrust bearing for said spindle in said frame, a reduced extension at the lower end of said spindle forming a shoulder which is supported on said bearing, said extension being adapted to prevent rotation of said spindle in said bearing but to permit axial displacement, a nut on said spindle, a presser plate supported on said nut, means on said presser plate for imparting rotation to said nut, a piston at the end of said spindle, a cylinder in which said piston is fitted to slide, and means for supplying fluid under pressure to said cylinder.

3. A press comprising a frame having an upright, a bolster plate, a threaded spindle fitted to slide in said frame but held against rotation, a nut on said spindle, a presser plate supported on said nut, means on said presser plate for imparting rotation to said nut, a piston at the end of said spindle, a cylinder in which said piston is fitted to slide, and a pump on said upright for supplying fluid under pressure to said cylinder.

4. In a press, a presser plate, a spindle for actuating said presser plate, mechanical means adapted to alternately displace said plate with respect to said spindle, and said spindle with respect to said plate, and hydraulic means adapted to exert thrust on said spindle.

5. In a press a self-contained frame comprising a base structure, uprights secured to said base structure, a presser plate in said frame, spindles on said uprights for actuating said presser plate, mechanical means adapted to alternately displace said plate with respect to said spindles, and said spindles with respect to said plate, and hydraulic means adapted to exert thrust on said spindles.

6. In a press a self-contained frame comprising a base structure, uprights secured to said base structure, a presser plate in said frame, spindles on said uprights for actuating said presser plate, transverse members on said uprights, hydraulic cylinders in said transverse members, pistons on said spindles mounted to slide in said cylinders, step bearings for said spindles in said base structure, mechanical means adapted to alternately displace said plate with respect to said spindles, and said spindles with respect to said plate, and hydraulic means adapted to exert thrust on said spindles.

In testimony whereof I affix my signature.
ADOLF FRIZ.
